UNITED STATES PATENT OFFICE.

CARL M. TICHENOR AND JAY SHOUP, OF CLYDE, OHIO.

WINDOW-SHADE AND CURTAIN-POLE BRACKET.

No. 931,002.

Specification of Letters Patent.

Patented Aug. 10, 1909.

Application filed November 2, 1908. Serial No. 460,731.

To all whom it may concern:

Be it known that we, CARL M. TICHENOR and JAY SHOUP, citizens of the United States, and residents of Clyde, in the county of San-dusky and State of Ohio, have invented cer-tain new and useful Improvements in Win-dow-Shade and Curtain-Pole Brackets, of which the following is a specification.

Our invention relates to devices for sup-10 porting window-shade and curtain-pole brackets, and has for its object the provision of means for supporting the brackets with-out employing nails or screws to secure them in position.

15 To this end our invention consists of angle plates secured in position by a clamp con-sisting of rods secured together by a turn-buckle for adjusting the clamp to the width of the window casing, said plates being pro-20 vided with beveled grooves to receive the bases of the brackets, which are secured in position by set-screws.

The details of our invention will be de-scribed hereinafter and illustrated in the ac-25 companying drawings, in which—

Figure 1 is a view of a fragment of a win-dow-casing with our improved device in po-sition thereon; Fig. 2, a front view, on an enlarged scale, of one of the supports; and 30 Fig. 3, a side view of the support and Fig. 4, a top edge view showing an end fragment of one of the clamping rods in position for insertion in the socket on the side of the support.

35 In the drawings similar reference char-acters indicate corresponding parts in all the views.

A indicates the window-casing, in which is secured the improved supports, consisting 40 of angle-plates 1, having on their front sides grooves 2, with beveled walls to receive the bases of the shade-brackets 3 and curtain-pole supports 4. The plates 1 are secured in position by means of a clamp 5, consisting 45 of rods 6, having their outer ends engaging sockets 7 in the sides of said plates, while their other ends are formed with screw-threads 8 to receive the turn-buckle 9, the threads on one rod being right-handed and

on the other left-handed, so that the clamp 50 is lengthened by turning the turn-buckle in one direction and shortened by turning it in the opposite direction. The outer ends of rods 6 are provided with laterally, extend-ing pins 10, that engage grooves 11 in sockets 55 7 to prevent them from turning in operating the turnbuckle.

12 indicates a pad of rubber, felt or other non-abrasive material secured in socket 13 on the inner side of plates 1 opposite sockets 60 7 to engage the window-casing and hold the plates in position without abusing the casing.

14 indicates screws to secure the brackets 3 and 4 from accidental displacement.

It will be understood that our improved 65 device insures securing the supports, at any desired height, to the window-casing with-out marring it with nail or screw holes, and that it may be easily removed, replaced, and adjusted. 70

Having thus described our invention, what we claim is—

1. In combination with a window-casing, angle-plates, said angle-plates provided with sockets having grooved walls, window-shade 75 and curtain - pole brackets adjustably se-cured to said plates, and an expansible clamp extended across said window-casing and en-gaging said sockets, said clamp provided with pins engaging the grooves in the sock- 80 ets, substantially as shown and described.

2. In combination with a window-casing, angle plates provided with sockets having grooves, window - shade and curtain - pole brackets secured to said angle-plates, rods 85 engaging said sockets and extending across the window-casing, said rods provided with pins engaging the grooves in the sockets and their adjacent ends threaded, and turn-buckles engaging said threaded ends, sub- 90 stantially as shown and described.

3. In combination with a window-casing, angle-plates having beveled grooves, curtain-pole and window-shade brackets having be-velled bases to engage said grooves, set-screws 95 secured in said angle-plates and engaging said bases, said angle-plates provided with sockets having grooved walls, rods engaging

said sockets and extending across the window-casing, said rods provided with pins engaging the grooves in the sockets and their adjacent ends threaded, and turnbuckles engaging said threaded ends, substantially as shown and described.

In witness whereof, we have hereunto set

our hands in presence of two subscribing witnesses.

CARL M. TICHENOR.
JAY SHOUP.
